UNITED STATES PATENT OFFICE

2,075,970

HAT HOLDER

Edwin W. Wood, Edmond, Okla.

Application May 6, 1935, Serial No. 19,956

2 Claims. (Cl. 24—255)

My invention relates to holders for hats, and more particularly to holders for installation upon the backs of seats in public meeting places such as vehicles, churches, theaters, and the like.

5 The prime object of the invention is the provision of a holder which will support a hat by engagement with its brim, and will at the same time provide a space thereon for displaying an advertisement.

10 Other objects are to provide a device of this class which is new, novel, practical and of utility; which is simple in construction; which is cheap to manufacture; which is neat in appearance; which will be durable; and, which will be efficient 15 in accomplishing all the purposes for which it is intended.

With these and other objects in view as will more fully appear hereinbelow, my invention consists in the construction, novel features, and combination of parts hereinafter more fully described, pointed out in the claims hereto appended, and illustrated in the accompanying one-sheet drawing, of which,

Figure 1 is a plan view of the device; 25 Figure 2 is a side elevational view, showing in dotted lines, operation of the device;

Figure 3 is a fragmentary elevational sectional view detailing a portion of the base plate; and,

Fig. 4 is a perspective view of the device with 30 the cover removed.

Like characters of reference designate like parts in all the figures.

It is understood that various changes in the form, proportion, size, shape, weight and other 35 details of construction, within the scope of my invention may be resorted to without departing from the spirit or broad principle of my invention and without sacrificing any of the advantages thereof; and it is also understood that the drawing is to be interpreted as being illustrative 40 and not restrictive.

The inventive idea involved is capable of receiving a variety of mechanical expressions one 45 of which, for the purpose of illustrating the invention, is shown in the accompanying drawing wherein:—

The reference numeral 1 indicates as a whole 50 a preferably flat base having a pair of spaced upstanding loops 2 and 3 at its lower end portion and having a plurality of perforations for receiving screws or the like 4 by which it may be connected to a suitable support such as the back of a theater seat or the like. A substantially U-shaped spring 5 has its end portions 6 and 7 dis-

posed flatly along the surface of the plate 1 and inserted through the loops 2 and 3. Each leg of the spring is provided with a convolution 8. A tongue 9 is disposed between the legs of the spring 5 with one end impinged by the cross-element 10 of the spring and the adjacent surface of the base 1. The spring normally retains the free end of the tongue 9 at the end of its throw lying most remote from the plate 1. Intermediate its ends the tongue 9 is provided with a fulcrum 11 upon 10 which it may rock.

Obviously the fulcrum 11 could be disposed upon or made integral with the base plate 1, if desired, instead of being made a part of the tongue.

15 The free end of the tongue 9 carries a rigidly mounted push button 12 by which that end of the tongue may be forced toward the plate 1 for moving the impinged end of the tongue away from the plate.

A suitable hood 13 having a visor 14 extending over the spring 5 and the tongue 9 and having its edges turned to form flanges 15 for embracing the edges of the plate 1 is disposed upon the plate 1 and has a frictional engagement with the plate. 25 The hood is installed upon the plate by inserting the plate into the open ends 16 of the slots formed by the body of the hood and the flanges 15. The screws 4 may or may not be disposed through the hood as well as the plate, as desired. The hood 30 is provided with a through perforation 17 through which the push button 12 projects.

An advertising medium, indicated generally by the reference numerals 18, is shown upon the hood. The hood and the base plate may be made 35 of any desired size and configuration.

In operation, manual pressure is exerted upon the push button 12 to raise the opposite end of the tongue 9. The brim of a hat, not shown, is inserted between the plate and the tongue and the pressure is released. Tension of the spring 5 impinges the brim between the tongue and the plate and thereby supports the hat.

Obviously, the invention is susceptible of embodiment in forms other than that which is illustrated in the accompanying drawing and described herein, and applicable for uses and purposes other than as detailed, and I therefore consider as my own all such modifications and adaptations and other uses of the form of the 50 device herein described as fairly fall within the scope of my invention.

Having thus described my invention, what is claimed and desired to be secured by Letters Patent, is:

50

55

1. A hat holder embodying: a base adapted to be secured to a seat back or the like; a substantially U-shaped spring member having its open ends secured to said base; a tongue longitudinally disposed within said spring member having a transverse notch in its lower end portion adapted to seat the closed end of said spring member, said spring member thereby normally holding the notched end portion of said tongue against said flat base; a fulcrum for said tongue; an outwardly extending push button on the free end of said tongue; and a removable cover for all of said members being open at its lower end to allow access to the notched end of said tongue, said cover having a suitably located perforation to allow movement of said push button therein.

2. A device of the class described comprising: a metal base substantially adapted to conform to

the back of a seat or chair; a U-shaped spring having one convolution in each of its shanks, said shanks secured rigidly at their open ends to said base; a tongue having a fulcrum contacting the base, being longitudinally disposed between the shanks of said spring and having its lower end impinged between the closed end of said spring and the base; an outwardly extending push button on the free end of said tongue; and a cover for said spring and tongue attached on three sides to said base member, and having its lower end open to allow the free insertion of an article between the lower end of said tongue and said base, said cover having a suitable perforation to allow manual operation of said tongue by means of pressure applied to said push button.

EDWIN W. WOOD.
